UNITED STATES PATENT OFFICE.

ROSS T. RUTH, OF WINTERSET, IOWA.

WALL-BOARD SUPPORT.

Application filed November 9, 1926. Serial No. 147,363.

This invention relates to supports and more particularly to a device by means of which a strip of wall board, such as beaver board or the like, may be held in engagement with ceiling rafters while it is being nailed to the rafters.

One object of the invention is to provide a support of this character by means of which the wall board may be firmly supported in close contacting engagement with the ceiling beams and prevented from moving out of proper relation to the ceiling beams or wall board already mounted.

Another object of the invention is to permit the support to be vertically adjusted so that it may be employed in rooms having ceilings of different heights.

Another object of the invention is to provide the support with an elongated body portion for engagement with the wall board to be supported and props for the body portion which may be folded and extend longitudinally beneath the same thereby permitting the support to be reduced to a compact mass and easily transported or stored in a small space.

Another object of the invention is to so construct the support that it will be of light weight and easy to move from one position in a room to another.

The invention is illustrated in the accompanying drawing, wherein

Figure 1 is a view showing the support in side elevation and a section of wall board being supported thereby;

Fig. 2 is a top plan view of the support;

Fig. 3 is a view in elevation looking at the inner face of one of the props, and

Fig. 4 is a view in elevation looking at the outer face of the other prop.

The wall board support constituting the subject-matter of this invention is provided with a body portion having side bars 1 connected by end bars 2 and 3 and braced intermediate its length by cross bars 4. The body portion will, therefore, be formed as an open frame and may very effectively support a strip of wall boarding without having excessive surface engagement therewith.

The prop at one end of the body is provided with side bars 5 connected at their upper ends by a head bar 6 and braced by a cross bar 7. It will be understood that, if desired, additional cross bars 7 may be provided. Each side bar 5 is provided with an auxiliary section 8 which fits against its inner

face and is held in engagement therewith by collars 9 and 10. The collars 10 are secured to the side bars 5 adjacent their lower ends, but the collars 9 are freely slideable and carry set screws 11 which, when tightened, will serve to firmly hold the extensions 8 in a set position with their lower end portions projecting downwardly the proper distance to retain the adjacent end of the body close to the ceiling. It will be obvious that, if desired, the collars 10 may also be provided with set screws. At its upper end, the prop is pivoted to the body by hinges 12 disposed adjacent the ends of the head bar 6 and attached to the under face of the body.

The prop for the other end of the body is formed, as shown in Fig. 4. Referring to this figure, it will be seen that instead of providing the prop with side bars 5 a single standard 13 is employed. The standard 13 is of the same length as the side bars 5 and at its upper end is secured to a crosshead 14 to which hinges 15 are secured. The hinges 15 are attached to the under face of the body.

It will thus be seen that this prop as well as the prop previously described may be swung to a folded position and will extend longitudinally of the body in overlying relation to each other. Braces 16 extend between the side faces of the standard 13 and end portions of the crosshead 14. Therefore, the standard and crosshead will be firmly held in proper relation to each other and danger of the standard being accidentally wrenched loose from the crosshead will be prevented.

An auxiliary section 18 is provided for the standard 13 and is held in engagement therewith by collars 19 and 20, corresponding to the collars 10 and 11. The collar 19 is secured to the standard adjacent its lower end and the collar 20 carries a set screw 21 which, when tightened, will firmly but releasably retain the extension in a set position.

When the support is in use, the props are swung downwardly to an operative position and the extensions 8 and 18 adjusted so that the body portion will be disposed adjacent the ceiling beams of the room. The strip of wall boarding 22 is slid into position upon the support and the props again adjusted so that the body will be elevated and the wall boarding moved into close contacting engagement with the ceiling beams. Nails or other fasteners will now be driven through the wall boarding into the ceiling beams and the props can then be lowered slightly to move the body

out of clamping engagement with the wall board and the support moved to a new position and the operation repeated until the entire ceiling has been covered with wall boarding. The extensions can then be retracted and the props folded so that they extend beneath the body and the support easily carried to a new place of use and stored in a small space.

10 Having thus described the invention, I claim:

A support of the character described comprising a body having side bars, cross bars extending between and secured against the ends of said side bars and bracing strips extending between the side bars and secured

against the under faces thereof in spaced relation to each other longitudinally thereof, and props for said body disposed at the ends thereof, each prop including upper and lower sections movable longitudinally of each other to adjust the height of the prop, means to releasably secure the lower section in a vertically adjusted position, a cross head at the upper end of said upper section hinged to said body and disposed below one of said cross bars parallel thereto and adapted to contact with the under face thereof to limit downward swinging movement of the prop beyond a vertical position.

30 In testimony whereof I affix my signature.

ROSS T. RUTH. [L.S.]
